UNITED STATES PATENT OFFICE

132,823

DESIGN FOR A BLACK-OUT SHOE OR SIMILAR ARTICLE

Grace M. Powell, New York, N. Y.

Application January 14, 1942, Serial No. 105,198

Term of patent 3½ years

To all whom it may concern:

Be it known that I, Grace M. Powell, a citizen of the United States, residing in New York city, in the county of New York and in the State of New York, have invented a new, original, and ornamental Design for a Black-Out Shoe or Similar Article, of which the following is a specification, reference being had to the accompanying drawing forming part thereof.

The essential feature of my design resides in the configuration of the flash light and holder attached to the throat of the shoe, and shown in solid lines.

I claim:

The ornamental design for a black-out shoe or similar article, substantially as shown and described.

GRACE M. POWELL.
